ELECTRIC CIRCUIT

Waldemar N. Olson, Brookfield, Ill., assignor to
 Reynolds Electric Co., Chicago, Ill., a corpora-
 tion of Illinois

Application March 20, 1944, Serial No. 527,210

7 Claims. (Cl. 315—120)

The invention relates to improvements in electric circuits for supplying an electric circuit with a substantially constant voltage from an electric circuit of variable voltage, the primary object of the invention being the provision of a system of circuits for the purpose which are of simple construction and highly efficient in use.

Other objects will appear hereinafter.

The invention consists of the combinations and arrangements of parts hereinafter described and claimed.

The invention will be best understood by reference to the accompanying drawing forming a part of this specification and in which—

Fig. 1 is a diagrammatic view illustrating circuits embodying the invention and shown in position of rest or non-use;

Fig. 2, a similar view showing the parts in the position assumed immediately upon excitation of the circuits;

Fig. 3, a similar view showing the positions of the parts assumed in the last stages of their operation; and

Fig. 4, a diagrammatic view illustrating a modified form of construction or arrangement.

The embodiment of the invention illustrated in Figs. 1, 2 and 3 comprises a main electric circuit 10, such as a series street lighting circuit in which the current flow is normally substantially constant, but the voltage varies in accordance with variable conditions in said circuit. A transformer 11 is connected as indicated, to transmit energy to a branch circuit 12 which, in this instance, is a flash lamp circuit, and includes, in series, a choke coil 13 and an incandescent lamp 14 and, in parallel, a film cut-out 15 as indicated. A by-pass circuit 16 is connected with said branch circuit on opposite sides of said choke coil and includes a normally open switch 17 operable by means of an electro-magnet 18, as indicated. A control circuit 19 is tapped into the choke coil 13 as indicated, and has its other end connected with the branch circuit 12, said control circuit including a thermostatic switch 20. A relay circuit 21 is connected with switch 20 and branch circuit 12 and control circuit 19 and includes the electro-magnet 18 of the switch 17.

By this arrangement, when current is supplied to the main circuit 10, the branch circuit 12 is also supplied with current through transformer 11, the parts then being in the position shown in Fig. 1. Some current will thus pass from the choke coil 13 to the control circuit 19 and thence to relay circuit 21, exciting the electro-magnet 18 and closing the switch 17, such action taking place

almost immediately after the supplying of current to the main circuit. As soon as the switch 17 closes, the choke coil 13 is by-passed, thus permitting sufficient current to flow through the lamp 14 to light the same, and the arrangement is such as to maintain a substantially constant voltage through said lamp as long as the switch 17 is held closed by the magnet 18. Continued flow of current through the thermostatic switch 20, however, heats said switch sufficiently to cause it to open after a predetermined time, as indicated in Fig. 3, whereupon the electro-magnet 18 is rendered inoperative and switch 17 automatically opens, thus in due course restoring the parts to the positions shown in Fig. 1 as soon as the thermostatic switch 20 closes sufficiently to close the control circuit, whereupon the operation will be repeated at predetermined and regular intervals.

As will be noted, when the by-pass circuit is closed, the current supplied to the control circuit 19 flows through the left-hand portion of the choke coil 13 instead of through the right-hand portion thereof as when the switch 17 is open. By varying the point at which the control circuit 19 taps the choke coil 13, the circuits may be varied to meet varying conditions so as to maintain a substantially constant voltage in the control circuit 19 during normal operations of the lamp 14, as will be readily understood by those skilled in this art. The film cutout 15 serves to protect the parts in case the lamp 14 should burn out or become inoperative, thus causing undue rise of voltage in the circuit. Under such circumstances the film cutout 15 will operate to by-pass the choke coil and thus prevent undue rise in voltage.

In the modification illustrated in Fig. 4, a stop switch 22 is employed in the control circuit 19 instead of the thermostatic switch 20, and a cam 23 is arranged to operate said switch as indicated; the cam 23 is carried by a cam shaft 24, operated through gearing 25 from the motor shaft 26 of the motor 27, and connected in and operated by the control circuit 19. As will be observed upon closing of the main circuit 10, the motor 27 will operate to open and close the switch 22, thus producing the same effects in the branch circuit 12 as indicated above and resulting in the periodic lighting of the lamp 14 while maintaining a substantially constant voltage in the control circuit 19, as will be readily understood by those skilled in this art.

While I have illustrated and described the preferred forms of construction for carrying my invention into effect, these are capable of variation and modification without departing from the

spirit of the invention. I therefore do not wish to be limited to the precise details disclosed, but desire to avail myself of such variations and modifications as fall within the scope of the appended claims.

I claim:

1. The combination with a main variable voltage circuit, of a branch circuit including a transformer transmitting energy from said main to said branch circuit and a choke coil; a control circuit having one end tapped into said choke coil and connected at its other end with said branch circuit; and means for utilizing said control circuit to maintain a substantially constant voltage in said control circuit.

2. The combination specified in claim 1 in which the main circuit is a series street lighting circuit and the branch circuit is a flashing lamp circuit.

3. The combination with a main variable voltage circuit, of a branch circuit including a transformer transmitting energy from said main to said branch circuit and a choke coil; a by-pass circuit connected with said branch circuit on opposite sides of said choke coil; a control circuit having one end tapped into said choke coil and connected at its other end with said branch circuit; and a relay circuit connected at its one end with said choke coil tap and connected at its other end with said branch circuit.

4. The combination specified in claim 3 in which the main circuit is a series street lighting circuit and the branch circuit is a flashing lamp circuit.

5. The combination with a main series street lighting circuit, of a branch circuit including a transformer transmitting energy from said main to said branch circuit; a choke coil and an incandescent lamp in series in said branch circuit; a by-pass circuit connected with said branch circuit on opposite sides of said choke coil; a normal open switch in said by-pass circuit; and a control circuit tapped into said choke coil at one end and connected at its other end with said branch circuit and including means for periodically opening and closing said switch.

6. The combination specified in claim 5 in which an electro-magnet is arranged to close said switch upon excitation; a thermostatic switch is included in the control circuit and arranged normally to maintain it closed, but open it through flow of current for a predetermined time; and a relay circuit is connected with said control circuit and includes and excites said magnet when closed.

7. The combination specified in claim 5 in which an electric motor is arranged in said control circuit to open and close said switch.

WALDEMAR N. OLSON.
